UNITED STATES PATENT OFFICE.

CLAUDE E. FLEMING, OF DETROIT, MICHIGAN.

CARBURETOR.

Application filed October 25, 1920. Serial No. 418,261.

To all whom it may concern:

Be it known that I, CLAUDE E. FLEMING, a citizen of the United States, residing at Detroit, in the county of Wayne and State of Michigan, have invented certain new and useful Improvements in Carburetors, of which the following is a specification.

This invention relates to carburetors, and has for its object a carburetor provided with an automatic regulation for the auxiliary air and also a manual control for the auxiliary air. A special form of float and needle valve is utilized.

One of the novel features of the carburetor is the arrangement of a fiber or felt wick through which a regulatable quantity of air is drawn to vaporize the fuel oil, as will be more fully explained hereafter.

In the drawings,—

Fig. 1 is a side elevation of the carburetor showing a part of the throttle chamber in section.

Fig. 2 is an elevation of the carburetor taken ninety degrees removed from Fig. 1 and showing the lower portion of the carburetor in vertical section.

Fig. 3 is a section on the line 3—3 of Fig. 2.

Fig. 4 is a section on the line 4—4 of Fig. 2.

Fig. 5 is an enlarged section of the lower portion of the carburetor showing how more air is admitted by pulling the draft rod.

Fig. 6 is a section on the line 6—6 of Fig. 2.

The carburetor is of simple construction, comprising simply a float chamber *a* formed by a casting upon which is mounted, by screwing thereto, a cylinder *b* which carries the auxiliary air intake and the control for the same, which will be presently described. The casting *a* is provided with a depending boss *c* forming a nozzle socket. The cap *d* that closes the lower end of the casting is provided with a projecting boss or air tube *e*. This has substantially the same configuration as the socket in the boss *c*. A wick *f* of fibrous material, such as loose felt, is adapted to fit over the air tube *e* and engage in the space between the air tube and the socket in the boss. This wick is adapted to raise the fuel oil contained in the float chamber by capillary action in a well known manner, and the wick obviously becomes saturated with this fuel oil. This wick is sufficiently porous to allow the passage of

air therethrough, which is introduced by the air tube *e* and which is provided with a relatively large central bore *g* communicating with an air valve chamber *h* and in which is arranged the air valve *i* which is never completely closed. A spring *j* engages between this air valve and the screw plug *k*. This screw plug is provided with air orifices *l*. A pair of lugs or arms *m* depend from this screw plug and are adapted to hold the pin *n* on which the cam *o* is pivoted. This cam *o* has a draft connection *p* that may be led to any convenient point as on the dash of the car. The bottom of the cam *o* engages with the cam follower *q* that is perforated and screw-threaded to receive the threaded valve stem *r*. The jam-nut *s* is also threaded onto this stem. The member *q* is adjustable on the stem.

The float is a cork ring *t* which engages about the boss *c* and which is secured to the float arm *u* by means of the continuation of this float arm that forms a clip *w* engaging three-quarters of the way around the cross section of the ring. A screw *x* secures this clip to the cork ring. The float arm *u* is pivoted at *y* and has secured to one side a needle valve *z*. *z* is a stop for the float arm and a limit for the needle valve. Obviously this float travels on an arc in rising and falling within the limit of its movement—the distance from the interior of the ring to the boss on an arc whose center is at *y*. This construction eliminates the usual counterweighted arms used on floats to convert the rising movement of the float into the descending movement of the needle valve and the drop of the float into rising movement of the needle valve. These counterweight levers are not only more expensive construction but they often result in trouble due to cramping on their bearings and sticking. I find that an oblique float, as shown, works much better as it travels upon an arc.

The throttle valve is designated 2 and the shaft 3 that carries the throttle valve is journaled in a continuation of the cylinder *b* that forms the auxiliary air intake. This continuation will be designated the throttle valve housing and is lettered 4. The arm 5 is attached to the throttle valve shaft and may be connected by the usual draft rod to the throttle lever on the steering post. Or the arm 30 may optionally be connected with the throttle lever on the steering post. A stub 6 on the member bearing arm 5 is adapt-

ed to be engaged by the point 7 of the adjusting screw 8 to adjust the idling speed of the motor at closed throttle. Nothing is claimed for these throttle connections. However, on the other end of the throttle shaft is secured an arm 9 which connects through a ball and socket joint 10 with a rod 11 that also connects through a ball and socket joint 12 with the revolving sleeve or shutter 13 that rotates on the exterior of the cylinder *b*. 14 designates a screen that is secured in the opening of the cylinder *b* and that guards the auxiliary air intake. The auxiliary air intake is a rectilinear opening through the cylinder *b*. Obviously the rotating sleeve 13 constitutes a shutter for uncovering more or less of this auxiliary air intake depending upon the throttle position. When the throttle is opened up wide this entire auxiliary air intake is automatically opened by reason of the ball and socket and rod connections 10, 11 and 12.

A manual control for the auxiliary air intake is afforded by the curtain 16 which is a thin sheet metal member that can be adjusted up and down the vertical posts 17 by loosening the thumb nuts 18 which engage with the screw studs 19 provided with heads at 20. The curtain may be adjusted simultaneously at both ends or one end may be adjusted slightly up or down with respect to the other end by reason of the slots 21 permitting a certain tilting. Obviously this regulates to a nicety the amount of auxiliary air at any given throttle opening. The throttle valve, as already explained, automatically opens up the auxiliary air intake in accordance with the throttle opening.

In starting the draft rod *p* is pulled, causing the rotation of the cam *o* to depress the cam follower *q* which carries the air valve downwardly, enlarging the air intake to allow a great amount of air to be drawn through the wick for the purpose of taking up a greater amount of the fuel oil fed by the wick.

The valve stem *r* by loosening the jam-nut *s* may be adjusted through the follower *q* to alter the amount of air entering through the air tube *e*.

The operation of the carburetor as regards the enriching of the mixture by enlarging the amount of air passing through the wick is as follows:

The wick is packed in between the air tube and the boss. If it weren't packed in this way and the suction were strong enough the raw fuel would be drawn up in such quantities as to make the construction impossible. It would operate in the same way a needle valve carburetor operates, except the quantities of fuel would be very large. With the wick packed in between the air tube and the boss socket only fuel oil fed up by capillary action is available. This fuel is

picked up by air passing through the wick. Now if a small quantity of air passes through the wick the saturation of the wick may be greater than that quantity of air can handle, but with a larger quantity of air, the air may pick the fuel up as fast as capillary action will feed it up into the top of the wick. Now this is the critical point and a further admission of air through the air tube would simply dilute the mixture. Only a small quantity of air, compared to the total amount of air goes through the air tube, in fact by screwing up the air regulating valve, it is possible to make the air for ordinary running a very small proportion of the total amount of air. Consequently if the wick is large enough it will feed more fuel oil than that small quantity of air can take up, hence an enlargement of the cross section of the air column will, within given limits, produce a richer mixture. The limit can be fixed by the shape of the cam.

What I claim is:

1. In a carburetor, the combination of a casing divided into a mixing chamber and a fuel reservoir connected by a passageway, a wick completely filling parts of said passageway so as to choke the same and prevent passage of fuel except that fed through the wick, said casing provided with a port for delivering air directly into the mixing chamber, and with a tube of relatively small air delivery capacity compared with said port for delivering air to the wick so as to cause the same to pass through the wick before entering the mixing chamber, and means for regulating the amount of air admitted to the air tube to enrich the mixture directly as the amount is increased up to the critical point, at which time all of the fuel fed up the wick is taken up by the air, completely saturating the same.

2. In a carburetor, the combination of a casing divided into a mixing chamber and a fuel reservoir connected by a passageway, the casing provided with a port for admitting auxiliary air to the mixing chamber, a curtain which can be given a set adjustment across the said port opening, and which may be also diagonally tipped to vary the port opening from side to side, and a rotary shutter operating in a direction substantially 90 degrees removed from the movement of the curtain in adjustment, the said shutter provided with connections by which it can be caused to automatically move with the throttle movement.

3. In a carburetor, the combination of a casing divided into a mixing chamber and a fuel reservoir connected by a passageway, a wick completely filling parts of said passageway so as to choke the same and prevent passage of fuel except that fed through the wick, said casing provided with a port for delivering the air directly into the

- mixing chamber and with a tube of relatively small air delivering capacity for delivering air to the wick so as to cause the same to pass through the wick before entering the mixing chamber, and means for regulating the amount of air admitted to the air tube under normal running conditions including devices for permitting an unusually large amount of air to enter the tube for starting said devices permitting the parts to return to the normal position of adjustment for running after starting.
4. In a carburetor, the combination of a casing divided into a mixing chamber and fuel reservoir connected by a passageway the said casing being provided with a down-
- wardly depending boss provided with a socket and with an upwardly extending air tube adapted to fit into the socket of the boss and a wick packed in between the interior of the boss and the exterior of the air tube, said casing provided with a port for delivering air directly into the mixing chamber and the said air tube delivering a small amount of air through the wick packed between the tube and the boss and means for regulating the amount of air admitted to the air tube.

In testimony whereof I affix my signature.

CLAUDE E. FLEMING.
